UNITED STATES PATENT OFFICE.

RANSOM S. ANGELL, OF MOORHEAD, MINN., ASSIGNOR OF ONE-HALF TO MARSHALL A. SPOONER AND FRANK D. LARRABEE, OF SAME PLACE.

TRACTION-ENGINE.

SPECIFICATION forming part of Letters Patent No. 314,285, dated March 24, 1885.

Application filed July 1, 1884. (No model.)

To all whom it may concern:

Be it known that I, RANSOM S. ANGELL, a citizen of the United States, residing at Moorhead, in the county of Clay and State of Minnesota, have invented certain new and useful Improvements in Traction-Engines; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

15 My invention relates to improvements in traction-engines or road-engines designed to draw loads on ordinary roads, or prairie gang-plows, or for analogous uses, and is intended as an improvement upon the engine patented 20 to me August 14, 1883, No. 282,944.

It also relates more particularly to the device for communicating motion from the engine to the drive-wheels, and to an improved method of constructing the forward or steering 25 wheels and steering device, as will herein-after more fully appear in the specification and be pointed out in the claims.

In my former patent above mentioned I did not describe any specific engine or boiler, but 30 claimed that any suitable one could be mounted on the carriage-bed of my device. In the present instance I will describe the attachments of the propelling mechanism with the drive-wheels by which my engine is propelled.

35 In the accompanying drawings, Figure 1 is a plan view of my engine. Fig. 2 is a sectional view of the forward wheels, the steering device, and its connections. Fig. 3 shows the connection of the propelling mechanism with the drive-wheels. Fig. 4 is a section of 40 one of the forward or steering wheels; and Fig. 5 is a detail view of the frame with the friction-rollers, drive-wheel, and tumbling-block.

45 A A is the carriage bed or frame on which the propelling mechanism is mounted, and B is the shaft or axle of the rear or drive wheels, which is placed below the bed, and C is the axle of the front or steering wheels, located 50 upon or over the bed. The shaft B is carried in bearings secured to the under side of the

bed, to bring said shaft near the ground, and it has on its center a gear-wheel, D, and at its ends are journaled the geared drive-wheels E, which are hung on the lower ends of T-shaped frames F, consisting of the vertical bar f and the cross-bar f', and mesh into the teeth of the circular racks G, which are secured to the inside of the rims or treads H, or may be cast integral therewith. The rack G is flanged on each side to receive and hold the drive-wheel E and the friction-rollers I, the latter being secured to the upper arm of the frame F, as the wheel E is to its lower arm or standard, by a short shaft. The main or rear wheels K, which are open metallic rims of broad tread, have within the metallic circular rack G, and they have no connection with the axle B except through the drive-wheels E and friction-rollers I on the frame F.

55 In an opening in the bed of the machine immediately above the axle B is journaled a short shaft, a, which carries a small gear-wheel, d, which engages with the gear-wheel D on the axle B. On this shaft a is also a sprocket-wheel, c, from which a chain, h, passes to another sprocket-wheel on a cross-shaft, x, on the engine, connected directly with the piston-rod.

60 The engine, which is the ordinary bed-engine, is mounted on the carriage-bed midway between the wheels, and the chain h extends from the cross-shaft x to the wheel c on the shaft a, or the engine and boiler may be mounted on feet secured to the carriage-bed.

65 From the inside of the upper bar, f', of the frame F a rod, f², extends down and is secured to a tumbling-block, e, on the axle B, near the wheel E, and a stop pin or rod, L, attached 70 to the carriage-bed, hooks over the rod f², and when an obstruction is met the revolution of the main wheel H is stopped and the wheel E climbs up the rack until it attains the height of the obstruction, when the wheel H will be 75 lifted over the same and recommence its revolution.

80 In backing the engine the stop-pin L prevents the forward motion of the frame F, which "centers" the wheel H as if it had a hub. The rod f² also serves to additionally strengthen and brace the frame F.

The wheel H is an endless self-laying track for the drive-wheel E to run on, and at the same time supports the rear end of the carriage-bed, while the frame F, with the drive-wheel E and friction-rollers I, serves as a hub to said main wheel or tread H in its revolution round the axle B. The motion of each wheel H is independent, though on level or unobstructed ground they will move regularly together.

The steering device consists of a turning post or stem, O, passing through a bolster mounted on the forward axle, C, and having on the lower end of said turning-post a double pulley, O', contained in a pivoted block, round which pulley pass two wire cables, o, the ends of which are secured to the semicircular hubs of the guide or forward wheels. These guide-wheels P consist of a solid rim, p, connected with an inner rim, p', by arms or spokes p². This is all of these wheels which revolve. Their attachment to the axle C is as follows: The inner rim, p', is provided with a semicircular hub, R, round which the wheel P revolves. From this semicircular hub rises a stem, R', which passes through a vertical opening in the end of the axle C, allowing the axle to rise and fall on the stem in the upper open half-space of the inner rim, p'. At the top of the stem R' is a pin, r, extending up to and into a chuck or rider, s, which clasps the sides of the inner rim, p', and holds the wheel steady at the top. Thus the axle C has a vertical motion on the stem R', and as it rests on the pivoted block V, which carries the double pulley O', it has also an oscillating motion on this block V, regulated and controlled by the guides S' and the bolster T and braces t. The axle C has on each side, near the wheels, guide-ways S, arranged to receive between them guides S', attached to the carriage-bed, which, with its vertical motion on the stem R', allow the axle to rise and fall when crossing inequalities of the ground. A slotted bolster, T, rests on the center of the axle, and is supported at

its ends by braces t, attached to the carriage-bed in front and rear of the axle, and these braces also serve to connect the axle C with the carriage-bed. An elongated slot, u, in the bolster permits the passage of the turning-post O, which also passes through the axle and into the pulley, and has at top a wheel or equivalent means for turning. Each wire cable o is connected at one end to the inside of the front of one of the semicircular hubs of a wheel, P, 55 and then passes round one of the sheaves of the double pulley O', at the foot of the stem O, and back to the rear of the hub, where it is secured.

It is obvious that turning the stem O to 60 right or left will change the direction of both guide-wheels P simultaneously.

It is designed to employ lifting-springs on the main wheels of my engine—such as are made the subject-matter of another application for patent by me now pending.

Having thus fully described my invention, what I claim therein as new, and desire to secure by Letters Patent, is—

1. In a traction-engine, the combination of 70 the forward axle, C, the wheels P, the turning-post O, the double pulley O', the wire cables o, the braces t, and the slotted bolster T, all as described.
2. In a traction-engine, the combination of 75 the main shaft or axle B, the tumbling blocks e, the stop-rod L, and the hooked rod f², with the drive-wheels E, and the carriage bed or frame, as described.
3. In a traction-engine, the combination of 80 the main axle B, the tumbling blocks e, stop-pin or rod L, hooked rod f², the frame F, carrying the drive-wheel and friction-rollers, and the endless track or tread, all as described.

In testimony whereof I affix my signature in 85 presence of two witnesses.

RANSOM S. ANGELL.
